(57) CLAIM

The ornamental design for a sofa arm front section, as shown and described.

DESCRIPTION

FIG. 1 is a perspective view of the sofa arm front section showing my new invention;

FIG. 2 is a front elevational view thereof;

FIG. 3 is a left-side elevational view thereof, with the right-side elevational view being a mirror image of FIG. 3; FIG. 4 is a rear elevational view thereof; and,

FIG. 5 is a top plan view thereof, with the bottom plan view thereof being a mirror image of FIG. 5.

The broken lines shown in the figures are for illustrative purposes only and form no part of the claimed sofa arm front section design.
